United States Patent Office

Des. 192,307

Patented Feb. 27, 1962

192,307

PASSENGER AIRCRAFT

Lawrence B. Rellis, 5123 W. Deming Place, Chicago, Ill.

Filed Aug. 11, 1960, Ser. No. 61,701

Term of patent 7 years

(Cl. D71—1)

FIG. 1 is a side elevational view of a passenger aircraft showing my new design;

FIG. 2 is a front elevational view;

FIG. 3 is a top plan view, and

FIG. 4 is a rear elevation thereof.

The side opposite that shown in FIG. 1 is a mirror image of the disclosed side.

I claim:

The ornamental design for a passenger aircraft, as shown and described.
